US0D1031126S

(12) **United States Design Patent** (10) **Patent No.:** **US D1,031,126 S**
(45) **Date of Patent:** **** Jun. 11, 2024**

(54) **LAMP**

(71) Applicant: **Shenzhen Mingtai Electric Appliance Industry Co., Ltd.**, Shenzhen (CN)

(72) Inventor: **Zengling Zhao**, Shenzhen (CN)

(73) Assignee: **Shenzhen Mingtai Electric Appliance Industry Co., Ltd.**

(**) Term: **15 Years**

(21) Appl. No.: **29/836,421**

(22) Filed: **Apr. 27, 2022**

(30) **Foreign Application Priority Data**

Jan. 6, 2022 (EP) 008818132-0001

(51) **LOC (14) Cl.** **26-05**

(57) **CLAIM**

The ornamental design for a lamp, as shown and described.

DESCRIPTION

FIG. 1 is a first perspective view of a lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the lamp that form no part of the claimed design.

1 Claim, 8 Drawing Sheets
